UNITED STATES PATENT OFFICE.

TIMOTHY J. SULLIVAN, OF HARTFORD, AND WILLIAM J. SULLIVAN, OF EAST HARTFORD, CONNECTICUT.

GEOMETRIC INSTRUMENT.

Application filed May 25, 1922. Serial No. 563,480.

To all whom it may concern:

Be it known that we, TIMOTHY J. SULLIVAN and WILLIAM J. SULLIVAN, citizens of the United States, residing at Hartford and 5 East Hartford, respectively, in the county of Hartford and State of Connecticut, have invented certain new and useful Improvements in Geometric Instruments, of which the following is a specification.

16 This invention relates to a geometric instrument, such for instance as is used by mechanical engineers, draftsmen, civil engineers, architects and other individuals for the purpose, among others of scribing angles of various degrees.

20 Among the objects of the invention are the provision of an article of the character set forth which is simple in construction, effective in action and by reason of which the maximum accuracy in various kinds of work is insured.

25 In the drawing accompanying and forming part of the present specification we have shown in detail several forms of embodiment of the invention which will be set forth fully in the following description. Obviously, we are in no sense restricted to this specific disclosure. We may depart therefrom in a number of respects within the 30 scope of the invention defined by the claims following said description.

Referring to said drawing:

Fig. 1 is a top plan view of a geometric instrument involving the invention, the 35 dotted lines showing one of the parts in an adjusted position.

Fig. 2 is a side elevation of the same.

Fig. 3 is a perspective view of the upper corner of the instrument.

40 Fig. 4 is a cross section on the line 4—4 of Fig. 1.

Figs. 5 and 6 are transverse sections on the lines 5—5 and 6—6 of Fig. 1.

45 Fig. 7 is a cross section on the line 7—7 of Fig. 6.

Fig. 8 is a detail view in top plan of a slight modification.

Fig. 9 is a sectional detail.

Fig. 10 is a section on the line 10—10 of 50 Fig. 2.

Fig. 11 is a section on the line 11—11 of Fig. 10.

Fig. 12 is a top plan view of a modification.

Like characters refer to like parts 55 throughout the several views of the drawing, these views being on different scales.

The appliance involves in its make-up a suitable foundation or base member which is intended to sustain the article upon which lines or the like are intended to be drawn. This article may be of any proper nature. For instance, it may be a book or series of sheets as 2 laid upon a base or foundation member such as 3 which generally consists 60 of a practically rectangular piece of wood, metal or composition material as desired upon which the pad or book 2 is laid, the base being of a little larger area preferably than the pad or book 2 although this is not 70 a vital consideration, nor is the shape of the respective parts.

We prefer to associate with the base or foundation 3, suitable bearing members such as those designated in a general way respectively by 4, each bearing member involving 75 in its make-up a body such as 5. Although these bearing members 4 may be located in any desirable place, they are desirably situated at the upper corners of the base or 80 foundation.

Each body 5 is practically of yoke form, its base being suitably rigidly attached to the upper side of the base or foundation member, its transverse portion 85 extending perpendicularly or at right angles to the base, and its upper branch being practically in parallelism with the lower or wider branch as shown in Fig. 1. The main or transverse portions of the respective bodies 5 may have associated with them on 90

their forward or lower sides the strip 6 having a resilient flange 7 to overlie the pad or book 2. As shown the transverse portions of the bodies 5 have in them vertically elongated slots 5' to receive the screws 6' threaded into the strip 6 to thus provide for adjustability of said strip 6 and therefore of the connecting flange 7, to conform to the thickness of the book or pad. The two 95

bearing members 4 constitute a convenient 100

means for sustaining a holding down or clamping member such as that denoted in a general way by 8 and which as we will hereinafter explain, yieldingly engages the upper sheet of the pad or book 2.

As shown there are disposed between the upper and the lower branches of the U-shaped bodies 5 the blocks 9 which have threaded through them, adjusting screws as

- 10 10 by which the blocks can be moved up or down or toward or from the bases of the U-shaped bodies 5, posts or pins as 11 extending freely through the respective blocks, supported by the bodies 5, and preventing 15 turning movement of the blocks 9. Through these blocks extends the shaft 12, the outer ends of which project laterally from the respective blocks and receive upon their extended ends coiled springs as 13, the inner 20 ends of which are desirably connected fixedly with the respective blocks and the outer ends of which act against the heads 14 and through which extend the extreme outer ends of the shaft or spindle 12. As 25 shown, these heads are at the upper ends of the side bars 15 of the yoke-like clamping member 8. These side bars may be rigid with the base or transverse portion 16 of said holding down or clamping member 8, 30 the base or cross portion 16 which is intended to bear against the lower portion of the uppermost sheet of the pad or book 2 is to facilitate its action, somewhat flattened and roughened on its inner surface. The 35 heads 14 have connected with them the respective springs 13 so that the springs can apply their effect to the holding down or clamping member 8.

- Extending between the sides 15 is a cross 40 member 17 which is desirably adjustable longitudinally of said side bars. This cross bar functions after the fashion of a rule and it has along its upper and lower portions, scales as 18 and 19 graduated as may be desired. 45 Its ends are somewhat forked, the branches of the forks 20 yieldingly straddling the respective side bars 15 so that the cross member or rule 17 may be readily applied to or moved from the side bars. One flange of 50 each of these clips 21 is a trifle longer than the other one so as to insure proper hold of the clips upon the side bars. The scaled member 17 has slidably on its upper side as shown the clip 22, the upper side of the clip 55 fitting flatwise against the top of the transverse or scaled member 17 and the branches thereof fitting rabbets or channels 23 in the sides of the scaled member near the lower surface thereof to thus prevent accidental displacement of the clip, yet when desired it can be readily removed or applied.

- From the upper side of the clip 22 the stud or pin 24 extends and has threaded to it the nut 25. This clip 22 constitutes a suitable supporting device or carrier for a pro-

tractor such as that denoted in a general way by 26. The protractor 26 as shown involves an inner section as 27 and an outer section as 28, the two portions being riveted or otherwise suitably united to each other. 70 The outer or main section 28 of the protractor 26 has at its upper end the clip support 29 which overlies the rule 30 functioning as a straight edge and which fits flatwise against the inner section 27 of the protractor, it being movable longitudinally of the protractor. It receives within it springs 31 attached at their butts to the protractor section 28 and the free portion of which fits a longitudinal channel 32 in the upper scaled member 30 to guide the upper scale 30. The upper and lower sides on the outer face of the rule have graduations as 33. The upper scaled member 30 is constantly at practically right angles to the body of the protractor 26 75 although as we have observed, it can be readily moved endwise. The scaled member 30 is generally at a constant angle to the protractor 26 and the graduations on the protractor are of such nature as to coincide at 80 all times with the center-line on the scaled member 17. By loosening the nut 25, the protractor 26 can be moved to any position upon the scaled member 17 and can be held in an adjusted position by tightening the 95 nut.

The scaled member 17 can as will be understood be readily moved along both side bars 15 for their complete length and both scales 18 and 19 on it can be used as well as 100 the scale on the side bar 15 at the left in Fig. 1. The protractor 26 can be used throughout the complete circle, so that maximum efficiency is insured. To facilitate the engagement of the holding down or clamping member 8 the lower cross bar 16 may as 105 shown in Fig. 9 have its lower face roughened or corrugated, as at 16a.

In Fig. 8 we have shown the holding down member of slightly modified construction. 110 In this event, the transverse member 16' at the lower end is longitudinally adjustable of the side bars or rods 15' and it may be held in an adjusted position by a set screw thereby adapting the structure to pads or 115 books of various depths. In this view (Fig. 8) the pad or book is denoted by 2' and the base or foundation member by 3'. In Fig. 12, the scaled member 17'' is the exact equivalent so far as manner of using the 12 scales is concerned, of the scaled member 17. Its body is removably associated with clips as 20'' which longitudinally slide on the side bars 15'' of a holding down member. The pad is denoted by 2''. The body 12 of the scaled member 17'' is detachably as sociable with the members 20'' and can be held removably associated therewith as by screws so that when the scaled member 17'' and the adjunct supported thereby is re- 13

moved from the members 20", the same can be used as a unit in drafting or engineering work.

The center-line of the scaled member 17 is intended to coincide with graduations on one of the side bars of the holding down member 8. In the illustration made in Fig. 1, this side bar is the one at the left. In the modification shown in Fig. 12, the scaled member 17 has the member 22" at the right. It will be understood that this scaled member 17" has centrally of its exposed surface a centerline which is intended to cooperate with a scale on the opposite side of the holding down member of which the side bar 15" is a part.

We wish to note the fact that the resilient flange 7 can be adjusted to conform to the depth of the book or pad by reason of the fact that the strip in question can be adjusted toward or from the base or foundation member 3.

What we claim is:

1. An appliance of the class described, comprising a foundation member to sustain an article to receive lines, bearing members supported at the upper side of the foundation member, a holding down member, and means for yieldingly forcing the holding down member against the article, a strip connected with the bearing members, and a flange connected with the strip, to overlie the article.

2. An appliance of the class described, comprising a foundation member to sustain an article to receive lines, yoke-like bearing members, the lower branches of which are attached to the foundation member, blocks supported between the branches of the bearing members, screws carried by the bearing members and threaded through the blocks, for adjusting the same, a shaft extending through the blocks, a yoke-like holding down member for the article, connected with the extended ends of the shaft, and springs around said extended shaft ends, connected respectively with the blocks and with said holding down member.

3. An appliance of the class described, comprising a foundation member to sustain an article to receive lines, yoke-like bearing members, the lower branches of which are attached to the foundation member, blocks supported between the flanges of the bearing members, screws carried by the upper branches of the respective bearing members and threaded through the blocks, for adjusting the same, guide pins carried by the respective bearing members and extending freely through the respective blocks, a shaft extending through the blocks, a yoke-like holding down member for the article, having heads connected with the extended ends of said shaft, and coiled springs around said extended shaft ends, connected respectively

with the blocks and with said holding down member.

4. An appliance of the class described comprising a foundation member to sustain an article to receive lines, yoke-like bearing members, the lower branches of which are attached to the foundation members, blocks supported between the branches of the bearing members, screws carried by the upper flanges of the respective bearing members and threaded through the blocks, for adjusting the same, guide pins carried by the respective bearing members and extending through the blocks, a yoke-like holding down member for the article, having heads connected with the extended ends of said shaft, coiled springs around said extended shaft ends, connected respectively with the blocks and with said holding down member, a strip connected with the inner side of the bearing members, and a resilient flange associated with the strip, to overlie the article.

5. An appliance of the class described comprising a foundation member to sustain an article to receive lines, bearing members supported by the foundation member, a holding down member sustained by the bearing members, means for yieldingly forcing the holding down member against the article, and protractor means carried by the holding down member.

6. An appliance of the class described, comprising a foundation member to sustain an article to receive lines, bearing members supported at the upper corners of the foundation member, a holding down member sustained at the upper corners of the bearing members, means for yieldingly forcing the holding down member against the article, and protractor means adjustably movable on the holding down member.

7. An appliance of the class described, comprising a scaled member, a clip to slidably straddle the scaled member, a stud rising from the clip, a securing device associated with the stud, a protractor adjustably turnable on said stud as a pivot, and a scaled member longitudinally adjustably supported by the protractor.

8. An appliance of the character described, comprising a scaled member, a clip to slidably straddle the scaled member, a stud rising from the clip, a nut threaded on the stud, a protractor turnable on said stud as a pivot and held in an adjusted position by said nut, and a scaled member longitudinally adjustably supported by the protractor.

9. An appliance of the character described, comprising a scaled member, a clip to slidably straddle the scaled member, a stud rising from the clip, a nut threaded on the stud, a protractor turnable on said stud as a pivot and held in an adjusted position by said nut, and a scaled member longitudi-

nally adjustably supported by the protractor, the second scaled member having a longitudinal channel and a spring carried by the protractor and fitted into the channel.

- 5 10. An appliance of the character described, comprising a foundation member to sustain an article to receive lines, bearing members supported at the upper side of the foundation member and a resilient flange extending between the bearing members to

overlie the article, and mounted for adjustment toward or from the foundation member.

In testimony whereof we hereby affix our signatures.
